UNITED STATES PATENT OFFICE.

CHARLES D. YOUNG, OF ALTOONA, PENNSYLVANIA.

FEED-WATER HEATER.

1,308,138.

Specification of Letters Patent. Patented July 1, 1919.

Application filed April 20, 1916. Serial No. 92,351.

To all whom it may concern:

Be it known that I, CHARLES D. YOUNG, a citizen of the United States, residing at Altoona, in the county of Blair and State of Pennsylvania, have invented certain new and useful Improvements in Feed-Water Heaters, of which the following is a specification.

The invention relates to feed water heaters and particularly to those for use upon locomotives and traction engines. The invention has for its primary objects the provision of a water heater adapted to utilize both the waste heat of the exhaust from the cylinders and that of the gases passing through the smoke box; the provision of a construction wherein the feed water heater in the smoke box is made to serve the function of a spark netting or screen; the provision of a construction arranged to cause the gases passing the heater to follow a tortuous path and absorb a maximum amount of heat from such gases; the provision of improved means for increasing the path of travel of the water through the tubes of the heater and the velocity thereof thus increasing the amount of heat absorbed by the heater and reducing the opportunity of scale formation; the provision of improved means for securing the tubes of the heater in place and for permitting the cleaning of the tubes; and the provision of improved positive means for keeping down the formation of scale upon the water tubes. Certain embodiments of the invention are illustrated in the accompanying drawings, wherein—

Figure 1 is a longitudinal section through the smoke box of a locomotive equipped with my feed water heating system; Fig. 2 is a front elevation of the apparatus of Fig. 1, the front end of the smoke box being removed; Fig. 3 is an enlarged section through one of the tubes of the heater in the smoke box; and Fig. 4 is a partial section through the front end of a smoke box provided with a modified type of heater, and Fig. 5 illustrates a further modification.

Referring first to the general arrangement, A is the smoke box of a locomotive of the ordinary type to which the gases of combustion are conducted through the fire-tubes B; C is the hood leading to the stack of the locomotive; D is the exhaust nozzle; E is the smoke box feed water heater which also acts as a screen for cinders or sparks;

and F is a feed water heater to which exhaust steam from the locomotive is conducted and in which the water is preliminarily heated.

The preliminary heater F is preferably located beneath the smoke box and may be of any desired type, the one shown being similar to that illustrated in my pending application, Serial No. 85,067, filed March 18, 1916. A conduit 1 (Fig. 1) supplies exhaust steam from the locomotive for heating the water in the heater F. The conduit 1 may take the steam from any point between the cylinders and the nozzle D, the point from which the steam is withdrawn being immaterial in so far as the present invention is concerned, and a number of points of withdrawal being illustrated in my application above referred to. The water to be heated is supplied through the pipe 2 (Fig. 1) and withdrawn through the outlet pipe 3 which leads into the passage 4 (Fig. 1) at the bottom of the heater E.

As shown in Fig. 1, the heater E is provided with two headers 5 and 6 and with four sets of pipes, 7, 8, 9 and 10. The lower header 5 is provided with three passages 4, 11 and 12 leading longitudinally thereof while the upper header 6 is provided with two passages 13 and 14 leading longitudinally thereof. Water supplied to the chamber 4 at the left-hand end thereof (Fig. 2) passes upwardly through the set of pipes 7 to the passage 13. It then circulates downward through the tubes 8 to the passage 11 and then up through the tubes 9 to the passage 14. From the passage 14 the water flows down through the tubes 10 to the passage 12, to the right-hand end of which is connected the outlet pipe 15 (Fig. 2) leading to the boiler.

Plates 16, 17, 18 and 19 (Fig. 1) are provided in the smoke box in order to cause the gases from the fire-tubes B to flow downward and to the front of the smoke box and then upward and to the rear through the heater E to the hood C, the heater E thus being made to act as a screen for cinders and sparks. In order to make the heater effective for this purpose the tubes are made relatively small and closely spaced, and the sets are staggered, as indicated in Fig. 1, so that the gases are forced to pursue a zig-zag path as they flow through the heater.

In order to still further increase the heating

capacity of the heater and render it more effective as a screening device, the V-shaped plates 20 are employed, the tubes of the heater extending through such plates and the entire 5 heater being galvanized to hold the plates in position and make a proper contact between the plates and the tubes. These plates are preferably made thin to increase their heat absorbing capacity and at inter- 10 vals heavier plates 21 are provided for spacing and supporting the tubes. The plates are preferably made V-shaped in cross-section, as indicated in Fig. 1, so as to give a double change to the direction of move- 15 ment of the gases and the angle is such that cinders and sparks will fall off of the plates by gravity. Either the plates or the tubes might be sufficient to perform the screening function, depending upon the 20 spacing, but taken together a still more effective screening is secured combined with a very efficient heat absorption.

The tubes are preferably held in place as indicated in Fig. 3, the lower ends being 25 threaded into the wall of the lower header 5, as indicated at 22, and the upper ends being expanded into the header 6, as indicated at 23. This prevents any relative 30 movement of the tubes with respect to the headers. In order to give access to the upper ends of the tubes the removable closure 35 plugs 24 are employed opposite the ends of the tubes (Fig. 1). Grooves are also provided in the header 5 at the lower ends of the tubes, as indicated at 25 in Fig. 3. These grooves become filled with the galvanizing material and serve to make the joints tight and prevent any accidental unscrewing of the tubes.

40 In order to keep down the scale in the tubes the rotatable spiral plates 26 are used. The flow of the water through the tubes causes these plates to rotate and not only prevents the formation of scale due to the 45 circular movement imparted to the water, but actually scrapes off such scale as it is formed and before it has an opportunity to become fixed in position. The tubes also serve to give the water a spiral movement, 50 thus increasing the distance which the water passes in traveling from one end of the tube to the other and also causing the water to move at a higher velocity. This is advantageous as the heat transfer from 55 the walls of the tubes to the water is increased.

Fig. 4 illustrates a modification of the heater in the smoke box, such heater having a modified header construction. The 60 lower header consists of two members 27 and 28 provided with the passages 29, 30 and 31, while the upper header consists of

the two members 32 and 33 provided with the passages 34, 35 and 36. The lower ends of the connecting tubes 37 are threaded into 65 the member 32 as in the other type of construction, while their upper ends are expanded into the member 33, also as shown in the construction of Fig. 3. Water enters the passage 29 from the inlet pipe 38. The 70 circulation of the water back and forth from one header to the other is substantially as heretofore described in connection with the structure of Fig. 1, the heated water finally reaching the passage 36 from which 75 it is discharged through the outlet pipe 39 leading to the boiler.

The upper plate 33 of the upper header is held removably in place by means of bolts, not shown, and upon the removal of 80 this plate access is given to the upper ends of the tubes 37. This arrangement has the advantage that the tubes 37 are accessible for cleaning and replacement from the outside of the smoke box. In this type of 85 construction the heat absorbing plates are not shown but might be used as in the construction of Fig. 1 or in a modified form.

Fig. 5 illustrates a modification of the spiral plates 26 of Fig. 3. In the modified 90 structure the spiral plate 40 is corrugated, such corrugations being shown as transverse but may be variously arranged. The purpose of the corrugations is to give a further agitation to the water flowing along the 95 plates.

The term "spark arrester" as found in the specification and claims is used in the sense in which such term is understood in the railroad art, namely, a device which will arrest 100 sparks of a size sufficient to cause fires adjacent the road bed.

What I claim is:

1. The combination with a locomotive having a smoke box with a passageway for 105 the gases from the locomotive fire-tubes, of a water heater located in such passageway and having its heat absorbing surfaces comprising closely spaced relatively small water tubes and transverse plates contacting with the tubes and arranged to form a spark and cinder netting.

2. The combination with a locomotive having a smoke box with a passageway for the gases from the locomotive fire-tubes, of 115 a water heater located in such passageway and having its heat absorbing surfaces comprising water tubes and transverse heat absorbing plates located thereon spaced closely enough to constitute a spark netting and 120 arrest sparks and cinders above a predetermined size.

CHARLES D. YOUNG.
